(57) **CLAIM**

The ornamental design for a inclined ultrasonic flow meter, as shown and described.

DESCRIPTION

FIG. 1 is a front left perspective view of a inclined ultrasonic flow meter according to the present invention.

FIG. 2 is a rear right bottom perspective view of the inclined ultrasonic flow meter shown in FIG. 1.

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines adjacent to the shaded or sectional portions forms and unclaimed boundary of the design. Any elements shown in in broken lines form no part of the claimed invention in this application and are show for environmental purpose only.
